UNITED STATES PATENT OFFICE.

JAMES C. SULLIVAN, OF NEW YORK, N. Y.

LOCK.

1,084,502.

Specification of Letters Patent. Patented Jan. 13, 1914.

Application filed January 24, 1913. Serial No. 743,942.

To all whom it may concern:

Be it known that I, JAMES C. SULLIVAN, a citizen of the United States, and a resident of the city of New York, borough of Manhattan, in the county and State of New York, have invented a new and Improved Lock, of which the following is a full, clear, and exact description.

The object of the invention is to provide a new and improved lock, more especially designed for use on handbags, valises, suit cases and other articles, and arranged to securely hold the article locked to enable the owner to readily open the article whenever it is desired to do so, and to prevent pickpockets and other unauthorized persons from surreptitiously opening the article.

In order to produce the desired result, use is made of a series of spaced keepers fixed on one member of the lock casing, a corresponding number of spring-pressed catches fulcrumed on the other member of the lock casing, and pins slidable in front of the lock casing member containing the catches and engaging the said catches to actuate the same, sundry of the said catches being in engagement with their keepers and others being out of engagement with their keepers so that the lock cannot be opened unless only those pins are pressed which control the catches in engagement at the time with their keepers.

A practical embodiment of the invention is represented in the accompanying drawings forming a part of this specification, in which similar characters of reference indicate corresponding parts in all the views.

Figure 1 is a perspective view of the lock; Fig. 2 is a central sectional view of the same on the line 2—2 of Fig. 4; Fig. 3 is a similar view of the same on the line 3—3 of Fig. 4; Fig. 4 is a longitudinal section of the same on the line 4—4 of Fig. 5; and Fig. 5 is a cross section of the same on the line 5—5 of Fig. 2.

As shown in the drawings, the lock casing consists of members A and B, of which the member A is in the form of a flat bar while the member B is hollow and adapted to abut against one face of the member A. On this face of the member A are formed or secured a number of keepers C each having two openings C' and C² located one above the other. The lower openings C' of the keeper C are adapted to be engaged by catches D fulcrumed at D' on a plate B' arranged in

the bottom of the hollow member B. Each catch D is pressed on by a spring E at one side of the fulcrum D' and the other side of the catch is pressed on by a pin F projecting through an opening in the front of the member B, as will be readily understood by reference to Figs. 1 and 2. The pins F are each connected with a catch D by means of a dowel on the pin engaging a recess in the catch. The catches D are so arranged that sundry of the same are normally out of engagement with their keepers while the remaining catches are normally in engagement with their keepers, as plainly indicated in Fig. 2, so that the two members A and B are normally locked together by those catches which engage their corresponding keepers. Now it will be noticed that a pickpocket or other unauthorized person trying to open the lock cannot do so unless this person knows which of the pins F to press inward in order to swing the corresponding locking catches into open position, that is, out of engagement with their keepers, as otherwise the lock cannot be opened. It will further be noticed that when a pin, which controls a catch which is normally out of engagement with its keeper, is pressed then such catch moves into engagement with the keeper and consequently the lock is further locked by this catch and keeper.

As shown in Fig. 2, three catches D are normally in engagement with their keepers and consequently if only one or two of these catches are actuated by pressing the corresponding pins F the lock cannot be opened as the remaining locking catch still engages its keeper. In a like manner if any of the other pins controlling a normally open catch is pressed such catch is moved into locking position to prevent opening of the lock. By the arrangement described it is next to impossible for a pickpocket or other person to open the lock with one hand, as is so frequently the case with handbags and like articles provided with the usual locking device.

The upper openings C² of the two middle keepers C are adapted to be engaged by tongues G' formed on a bolt G mounted to slide on top of the partition B² secured in the member B, the said bolt G being controlled by a key adapted to be inserted through a keyhole B³ arranged in the top of the member B. The key is adapted to engage a keyhole pin H held on the partition

B² to permit of conveniently turning the key for moving the bolt G into open or closed position. The bolt G is pressed on by a spring I (see Fig. 4) and the bolt is held 5 against accidental movement by lugs B⁴ and B⁵ struck up on the partition B² and engaging corresponding recesses in the under side of the bolt G.

It will be noticed that the owner of the 10 article provided with the lock can readily press the proper pins F with the fingers of one hand to disengage the corresponding catches D from their keepers to open the article, and it will further be noticed that 15 when the pressure on the pins F is released the catches and their pins return immediately to normal position. When it is desired to permanently lock the article the bolt G is moved into locking position by the key. 20 The catches D are alike in construction and may be interchanged so as to permit the user to change the combination, if desired.

The lock shown and described is simple and durable in construction and can be 25 readily applied to various articles, it being understood that in case the lock is attached to handbags, valises and the like, the frame members of such articles may form the members A and B.

30 Having thus described my invention, I claim as new and desire to secure by Letters Patent:

1. A lock, comprising a lock casing having two members, a series of spaced keepers 35 fixed on one casing member, a corresponding number of pivoted and spring-pressed catches in the other casing member, each catch being mounted on an independent pivot and adapted to engage one of the 40 keepers, and pins slidable in the casing member and engaging the said catches to actuate the same, sundry of the said catches being normally in engagement with their keepers and the others being normally out of engagement with their keepers so that the 45 lock is normally locked and can only be unlocked on simultaneously actuating all the catches normally in engagement with their keepers.

50 2. A lock, comprising a lock casing having two members, a series of spaced keepers fixed on one casing member, a corresponding

number of spring-pressed catches fulcrumed on the other casing member, pins slidable in the casing member and engaging the said 55 catches to actuate the same, sundry of the said catches being normally in engagement with their keepers and the others being normally out of engagement with their keepers so that the lock is normally locked and can 60 be unlocked only on simultaneously actuating all the catches normally in engagement with their keepers, and a key-controlled bolt mounted to slide on the member engaging the said catches, the said bolt having prongs 65 adapted to engage sundry of the said catches.

3. A lock, comprising a lock casing having a plate member and a hollow member provided with a partition, a series of keepers held on the plate member and each having 70 two openings opening into the hollow member above and below the partition, a series of spring-pressed catches fulcrumed in the hollow member below the partition to co-act with the corresponding openings in the 75 keepers, pins slidable in the front of the hollow members and controlling the said catches, a key-controlled bolt in the hollow member above the partition and provided with tongues engaging corresponding open- 80 ings in the keepers.

4. In a lock of the character described, a casing having a plurality of openings in two opposing sides, a plate having a plurality of apertured keepers projecting into 85 the casing through the openings in one side of the casing, a plurality of pivoted and spring-pressed hook-shaped catches corresponding in number to the keepers, each catch being mounted on an independent 90 pivot and adapted to engage one of the said keepers, and pins slidable in the openings in the other side of the casing and engaging the catches, sundry of the catches being normally in engagement with their keepers and the others being normally out of engagement with their keepers.

In testimony whereof I have signed my name to this specification in the presence of two subscribing witnesses.

JAMES C. SULLIVAN.
